UNITED STATES PATENT OFFICE

156,331

ANIMAL FEEDING TROUGH

Louise C. French, Washington, D. C.

Application July 15, 1948, Serial No. 147,576

Term of patent 14 years

(Cl. D12—2)

To all whom it may concern:

Be it known that I, Louise C. French, a citizen of the United States, residing at 3016 Cambridge Place, N. W., Washington, District of Columbia, have invented a new, original, and ornamental Design for an Animal Feeding Trough, of which the following is a specification, reference being had to the accompanying drawing, forming part thereof.

Figure 1 is a perspective view of the animal feeding trough, showing my new design.

Figure 2 is a side elevation of my animal feeding trough.

Figure 3 is a vertical section on the line 3—3, Figure 2.

Figure 4 is a bottom plan view of my animal feeding trough.

I claim:

The ornamental design for an animal feeding trough, as shown.

LOUISE C. FRENCH.
